UNITED STATES PATENT OFFICE.

ARTHUR A. WOLF, OF PHOENIX, ARIZONA.

EGG TESTER.

Application filed October 5, 1921. Serial No. 505,536.

To all whom it may concern:

Be it known that I, ARTHUR A. WOLF, a citizen of the United States, residing at Phoenix, in the county of Maricopa and State of Arizona, have invented certain new and useful Improvements in Egg Testers, of which the following is a full, clear, and exact description.

My invention relates to an egg tester and has for its object to provide such a device which is simple in construction, made of few parts and can be easily carried from place to place.

Another object of the invention is the provision of a portable dark room which forms a part of the tester and permits of the use of the tester out in the open during the day.

Other objects and advantages of the invention will be apparent from the following description when taken in connection with the accompanying drawing, in which,

The figure is a vertical section through the apparatus.

Referring to the drawing more in detail, the numeral 1 designates generally the egg tester which comprises a casing 2, electric bulb 3 and reflector 4.

Arranged at the proper distance from the source of light 3 is a lens 6 for focusing the light on the eggs to be tested. It is necessary, of course, that the eggs be shielded from outside light rays, and to this end the open end of the casing 2 is threaded to receive the threaded end of a cylindrical receptacle or dark room 14 in which is fixed a partition 13; the partition being apertured as indicated at 18 to serve as a guide for properly positioning the eggs before the light 3.

Extending upwardly from the receptacle 14 is an observation shaft 15 in which is

mounted a lens 16 for focusing the light rays, and a flexible curtain or screen 17 is secured to the remote end of the receptacle 14 for the purpose of excluding to a considerable extent the exterior light while an egg is undergoing examination. 45

In operation the egg to be tested is positioned against the partition 13 and in front of the opening 18, the curtain 17 being raised slightly for this purpose. Through the medium of the lens 6 the rays from the source of light 3 will be concentrated on the egg while the lens 16 forms an image which may be viewed by the observer who applies his eye to the upper end of the observation shaft 15. 50

From the foregoing description taken in connection with the accompanying drawing, it will be apparent that I have devised a relatively simple construction for candling eggs, which is composed of few parts and which may be easily assembled and disassembled for cleaning, repairs and the like. 60

Having fully described my invention, what I claim as new and desire to secure by Letters Patent is:—

A device of the class described comprising a cylindrical casing, a light reflector mounted in said casing, an electric lamp socket extending through the reflector and the end of the casing, an open-ended cylindrical receptacle threaded to said casing, a lens in said casing, an apertured rigid partition in said receptacle intermediate the ends thereof and adjacent the lens, a vertically extending shaft attached to said receptacle, a lens in said shaft, and a flexible curtain closing the end of the receptacle remote from the reflector. 70 75
